UNITED STATES PATENT OFFICE

LEE M. WILEY, OF MARION, INDIANA, ASSIGNOR TO DELTA ELECTRIC COMPANY, OF MARION, INDIANA, A CORPORATION OF INDIANA

REFLECTOR ASSEMBLY

Application filed June 16, 1930. Serial No. 461,384.

This invention relates to the reflector and lamp assembly of electric lanterns or flashlights and has for its primary objects to provide means for locking the lamp in focus and to reduce manufacturing costs.

Other and further objects and advantages will become apparent as the disclosure proceeds and the description is read in conjunction with the accompanying drawings in

10 which Fig. 1 is a perspective view of the base of a reflector provided with a single lead lamp socket thread;

15 Fig. 2 is a perspective view of the lock nut employed to hold the lamp in proper adjustment;

Fig. 3 is a vertical sectional view through the reflector assembly showing a lamp and lock nut in place; and

20 Fig. 4 is a rear view of the same.

Reflectors of the type now in use are usually equipped with a tubular socket which extends rearwardly from the base of the reflector and is threaded to receive the screw base of the lamp. When the lamp is screwed firmly in place, it is supposed to be in focus, but such is seldom the case because of inaccuracies in the manufacturing processes and the wear on the parts.

25 Another difficulty with the old type of reflector assembly is that the lamp often becomes loose within its socket causing the focus to be destroyed and many times resulting in a failure of the base of the lamp to make contact with the battery cell terminal.

30 Referring now to the drawings, the reflector 10 is of the usual semi-spherical or parabolic form, the base being slightly raised at 11 and apertured at 12 leaving an annular marginal flange 13. The inner surface 14 of the reflector is nickel or chrome plated as usual.

35 A single punching operation is all that is necessary to extrude a helical lip 15 from the flange 13 which begins at a point 16 and extends approximately half way around the flange where a radial slit 17 is necessarily formed.

The pitch of the helical lip is approxi-
50 mately twice that of the screw base so that

the distance between the edge 18 of the flange and the point 19 of the lip would be substantially the pitch of the thread on the lamp base. Since the lamp is intended to fit rather loosely within the reflector socket the approximations in the forming of the single lead thread in the reflector do not affect the accuracy of the focus obtainable, since the lock nut, hereinafter to be described, firmly holds the lamp in its proper position.

55 A preferred lock nut 20 is shown in Fig. 2 and is formed by extruding a helical lip 21 from a relatively thin washer 22, the process being exactly the same as that described with reference to the reflector. The slit 23 formed in making the helical lip is somewhat less in length than the width of the annular member so that the outer wall of the nut remains intact. To facilitate turning, the outer edge of the nut is scalloped, as 60 shown at 24.

65 The reflector assembly is shown clearly in Fig. 3 where the cooperation between the rounded threads 25 of the screw base, the lamp 26, the reflector socket consisting of the single lead thread, and the lock nut is made 70 most apparent.

75 As will be noticed, the crowding of the annular flange 13 of the reflector and the inner wall of the lock nut into the hollow of the lamp threads accomplishes a most satisfactory locking of the lamp within the reflector.

80 The single lead threads in the reflector and the lock nut may, of course, be formed in other ways than the one described, as for example by having the lip extend clear around the aperture, and it will be understood that many other details may be varied without departing from the spirit of this invention, the 85 scope of which is indicated in the appended claims.

I claim as my invention:

90 1. A flashlight reflector provided with an aperture, the material of the reflector about the aperture forming an inwardly directed flange broken at one point and formed to provide a screwthread having a single convolution, a lamp having a screwthreaded base adapted to be engaged with the reflector aperture, and a locking nut adapted to be 95 100

engaged with the base behind the reflector to lock the base and reflector tightly together.

2. A flashlight reflector provided with an aperture, the material of the reflector about the aperture forming an inwardly directed flange broken at one point and formed to provide a screwthread having a single convolution, and a locking disk having an opening, the material of the disk about the opening being broken at one point and formed to provide a screwthread similar to that of the reflector, in combination with a lamp having a screwthreaded base adapted to be engaged and locked with the reflector and locking disk threads.

3. A flashlight reflector provided with an aperture, the material of the reflector about the aperture forming an inwardly directed flange broken at one point, a portion of the flange being struck out in one direction from the plane of the remainder of the flange to provide a screwthread having a single convolution, a lamp having a screwthreaded base adapted to be engaged with the reflector aperture, and a locking nut adapted to be engaged with the base behind the reflector to lock the base and reflector tightly together.

In testimony whereof I affix my signature.

LEE M. WILEY.
